(57) **CLAIM**

The ornamental design for a set of three beard templates, as shown and described.

DESCRIPTION

FIG. 1 is a front view of a set of three beard templates having angled side pieces;

FIG. 2 is a front view of another embodiment of a set of three beard template having curved side pieces;

FIG. 3 is a perspective view of the mouthpiece template of a set of three beard templates of FIGS. 1 and 2 shown separately for convenience of illustration;

FIG. 4 is a front view of the mouthpiece template of a set of three beard templates;

FIG. 5 is a rear view of the mouthpiece template of a set of three beard templates;

FIG. 6 is a left side view of the mouthpiece template of a set of three beard templates;

FIG. 7 is a top view of the mouthpiece template of a set of three beard templates;

FIG. 8 is a bottom view of the mouthpiece template of a set of three beard templates;

FIG. 9 is a perspective view of the right side piece of a set of three beard templates of FIG. 1 shown separately for convenience of illustration, the left side piece being a mirror image;

FIG. 10 is a right side view of the right side piece of a set of three beard templates of FIG. 1 shown separately for convenience of illustration, the left side piece being a mirror image;

FIG. 11 is a left side view of the right side piece of a set of three beard templates of FIG. 1, the left side piece being a mirror image;

FIG. 12 is a front view of the right side piece of a set of three beard templates of FIG. 1, the left side piece being a mirror image;

FIG. 13 is a rear view of the right side piece of a set of three beard templates of FIG. 1, the left side piece being a mirror image;

FIG. 14 is a top view of the right side piece of a set of three beard templates of FIG. 1, the left side piece being a mirror image;

FIG. 15 is a bottom view of the right side piece of a set of three beard templates of FIG. 1, the left side being a mirror image;

FIG. 16 is a perspective view of the right side piece of a set of three beard templates of FIG. 2 shown separately for convenience of illustration, the left side piece being a mirror image;

FIG. 17 is a right side view of the right side piece of a set of three beard templates of FIG. 2, the left side piece being a mirror image;

FIG. 18 is a left side view of the right side piece of a set of three beard templates of FIG. 2, the left side piece being a mirror image;

FIG. 19 is a front view of the right side piece of a set of three beard templates of FIG. 2, the left side piece being a mirror image;

FIG. 20 is a rear view of the right side piece of a set of three beard templates of FIG. 2, the left side piece being a mirror image;

FIG. 21 is a top view of the right side piece of a set of three beard templates of FIG. 2, the left side piece being a mirror image; and,

FIG. 22 is a bottom view of the right side piece of a set of three beard templates of FIG. 2, the left side piece being a mirror image.
